UNITED STATES PATENT OFFICE.

HAROLD BROWNE, OF NOTTINGHAM, ENGLAND, ASSIGNOR TO PATCHOGUE MANUFACTURING CO., OF PATCHOGUE, NEW YORK.

DESIGN FOR A LACE CURTAIN.

No. 38,256.

Specification for Design.

Patented Sept. 25, 1906.

Application filed August 8, 1906. Serial No. 329,776. Term of patent 7 years.

To all whom it may concern:

Be it known that I, HAROLD BROWNE, a subject of the King of Great Britain, residing at Fletcher Gate, Nottingham, England, have invented a new, original, and ornamental Design for Lace-Curtains, of which the following is a specification, reference being had to the accompanying drawing, forming a part thereof.

The figure is a plan view of the curtain, showing the new design.

I claim—

The ornamental design for a lace-curtain, as shown.

HAROLD BROWNE.
